UNITED STATES PATENT OFFICE.

WILLIAM J. BRYON, OF NEW YORK, N. Y.

DOOR CLOSER AND CHECK.

1,364,830.

Specification of Letters Patent.

Patented Jan. 4, 1921.

Application filed May 8, 1915. Serial No. 26,807.

To all whom it may concern:

Be it known that I, WILLIAM J. BRYON, a citizen of the United States, residing in the city, county, and State of New York; have invented certain new and useful Improvements in Door Closers and Checks, of which the following is a full, clear, and exact description.

This invention relates to novel and useful improvements in door closers and checks, and has special reference to that type in which a plurality of cushions are provided to check the closing movements of the door, and also where the parts thereof are unconcealed by connection with the door and overhead casing in the usual manner.

One of the objects of the invention is to provide an improved door closer and check in which the chamber or chambers for containing respectively the closing means as a spring, and the checking mechanism constituting the cushioning means above referred to, are noncommunicating, and in which the operating spindle or post of the device has connection with a piston movable in the cylinder portion of the chamber containing the checking mechanism, by means of a crank and link or connecting rod in which the pivot or wrist pin of the latter operates with the piston to produce a valve designed to control the checking operation.

Another object is to provide for two cushions, the first of which is operative during the initial closing of the door, while the second or positive cushion is operative when the door has reached a point in close proximity to the latching position, so that slamming or closing of the door with undue force and jar is obviated.

Another object is to provide an improved adjustable pivotal link connection between the lever arm of the door closer and check and the lintel or overhead casing forming a part of the frame, whereby adjustment of the length of the link can be accomplished without removing the split portion thereof from the lever arm, thereby preventing the door from moving to a closed position. The adjustment of the length of the link also serves the purpose of timing the automatic valve above referred to and in this connection serves to control or regulate the operation of the cushions in order to bring the positive cushion into operation at the proper time.

Another object is to provide a device which

will not be likely to get out of working order and which will be durable, efficient and positive in operation. With the above and other objects in view, the invention consists in the novel combinations and arrangements of parts as will be hereinafter more fully described and claimed.

Reference is to be had to the accompanying drawings forming a part of this specification, in which like reference characters indicate corresponding parts throughout the several views and in which:

Fig. 1 is a plan view showing the improved door closer and check in position, portions of the door and casing being shown in section.

Fig. 2 is an enlarged vertical sectional elevation of the device taken through the casting thereof.

Fig. 3 is a horizontal sectional view through the chamber of the checking mechanism as shown in Fig. 2.

Fig. 4 is a fragmentary sectional view showing the connection between the crank and the piston, with the parts positioned when the valve is closed.

Fig. 5 is an enlarged fragmentary sectional elevation the section being taken on a line longitudinal of the adjustable link to more clearly define the structure thereof.

Fig. 6 is a cross sectional view taken on line 6—6 of Fig. 5.

Fig. 7 is a detail sectional view of a modified form of adjusting means for the link.

In the drawings the door closer and check are shown or illustrated as comprising a casting in the form of a casing 10, including a chamber 11, adapted to inclose the closing means or spring 12, while 13 designates the chamber for inclosing the checking mechanism. This chamber is separated or made non-communicating with respect to the chamber 11, by an intermediate partition or wall 14, and is provided with a cylindrical portion 15 closed by an air tight cap 16 in the usual manner. A vertical spindle or post 19 is journaled to oscillate in the horizontal walls produced by the bottom of the casing 10 on the bottom of the chamber 13 in a bearing 16' and through a packing gland 17 in the partition or wall 14, as well as through a cover 18 secured in an air tight connection to the top of the cylindrical chamber 11, inclosing the spring 12, the upper end of which spindle or post is squared for the attachment 110.

of a lever arm 20, rigid therewith and suitably retained from displacement. The spring 12, constituting the closing means is connected to the casing at the chamber portion 11 and also to the arm within said chamber, such connection being effected with the arm through the medium of its double ratchet mechanism including a square toothed ratchet wheel 21, having connection 10 with the spring and engaged by a double acting pawl 22 carried by the arm. This latter structure is general and well known, and no novelty is claimed therefor, as any other connection may be made between the spring 15 and lever arm as is desired. As the chamber 13 is designed to contain air or other suitable non-freezing fluid or liquid, the packing gland 17 besides serving as the bearing for the spindle or post 19, also prevents the escape of such fluid or air into the chamber 11 to interfere with the cushioning action which will be hereinafter explained.

The spindle 19 is formed with a crank 23 and operating in the cylindrical portion of 25 the chamber 13 is a piston 24 having connection with the crank 23 through the medium of a link or connecting rod 25, whereby during the oscillation of the spindle, the piston will be reciprocated in the usual manner, due 30 to the connection of the door closer and check proper through the medium of an attaching portion 26 with a door 27 hinged or swinging in a frame 28. The free end of the lever arm 20 has connection with the 35 lintel or overhead casing 29 or the door frame by an improved adjustable link 30, the construction of which will more clearly appear hereinafter.

The piston 24 is provided with one or 40 more valved passageways 31 to avoid a drag on the door when initially opened, by permitting the free escape of the fluid thereby through the crank end of the chamber 13 to the portion 15 thereof and the pivotal connection of the link or connecting rod 25 cooperates with the piston to produce a valved passageway constituting means to produce a plurality of cushions effective during the closing of the door. In the present instance, 45 two cushions are provided, the first or primary cushion being operative during the initial closing of the door, to a point in close proximity or adjacent to the latching thereof, while the second or positive cushion 50 then takes effect to considerably check the movement of the door to prevent closing thereof with undue force and jar. For this purpose the piston is provided with a passageway 32 of suitable cross section leading 55 entirely through the same and the pivot or crank pin of the link or connecting rod 25, which may take the form of a leg 33 projecting from said link or connecting rod and held from displacement by the crank 60 23 to which the link is pivotally connected,

cooperates with a seat 34 forming a channel in the piston diametrically of the latter, said pivot, wrist pin or leg also having a diametrical passage 35 of suitable cross section to coöperate with the passage 32, whereby 70 communication between opposite sides of the piston in the chamber may be established or cut off. As will be clearly seen from Figs. 2, 3 and 4 of the drawings, when the door is open, being usually swung in an arc of 75 about 85° or 90°, or possibly 180° the spindle or post 19 will be oscillated against the action of the spring 12 as the lever arm 20 is oscillated by the swinging of the door through the medium of the link connection 80 30, with the result that the pivot will be oscillated to bring the passages 32 and 35 into alinement during the initial closing of the door to permit the escape of the fluid from in front of the piston to the crank 85 end of the chamber 13, while the initial cushion is operative. The position of the parts during this operation is shown in Figs. 2 and 3 of the drawings. However, when the piston has traveled its full stroke during the complete oscillation of the lever arm and spindle, or for instance to the position shown in Fig. 4, the passage 35 will be moved out of alinement with the passage 32 so that the passage 32 will be closed and 90 communication cut off from opposite sides of the piston, thus producing a positive cushion in front of the piston by the additional pressure or resistance offered. This positive cushion checks the closing of the 100 door adjacent to the latching position while the slow escape of the fluid thereafter between the inter-fitted parts of the cylinder, piston, will suffice to permit the piston to move its full stroke under the action of the 105 closing means or spring so that the door will close or latch without undue force, jar or noise incident thereto. This closing is positive and when once adjusted will not vary the fraction of an inch, thus avoiding the 110 constant annoyance occasioned by devices for this purpose employing physical working valves.

The adjustable link 30 serves as a means for regulating the effective action of the cushion. As illustrated, said link has a pivotal connection with the lintel or overhead casing 29 through the medium of a swivel connection 36. The link includes a section or part 37 externally threaded on its free end and loosely passed through a longitudinal aperture 38 in a split section or part 39 swiveled and clamped against displacement as shown at 40 to the free end of the lever arm 20. An adjusting nut has a 120 screw threaded connection with the adjusting screw or section 37 at the threaded end of the latter, and is held from displacement within an opening or reamed out portion 42 of the split section 39. The nut is rough- 125 130

ened or milled as shown, to permit it to be easily turned and thereby adjust the parts longitudinally or telescopically with relation to each other to permit adjustment of the length of link without disconnecting the same with respect to the lever arm, or requiring the arm to be manually held against the tension of the closing means or spring while the adjustment is being accomplished. The adjustment of the arm serves to turn the spindle or post 19 and thereby oscillate the valve formed by the pivot or wrist pin 33, due to the lengthening or shortening of the link 30, thus to regulate the time at which the valve serves to bring the passageways 35 into alignment with the passageway 32 or to cut off the passageway 32 and to bring the last part of the cushion or the positive cushion into play. It will also be noted from Fig. 3 that one end of the passageway 35 is slightly widened in order to allow for this adjustment in such a manner that when the door is open the valve will be entirely open and will gradually close until the door reaches a point in close proximity to the latching position.

As a means for holding the nut in an adjusted position after the length of the link 30 has been regulated, a pivoted latch 43 may be mounted at one side of the section 39 and provided with an extension 44 to engage in one of a series of longitudinal notches 45 in the nut to prevent the latter from turning while the latch is held against displacement when so engaged by means of a spring or holding device 46. By this means any play between the parts is taken up and a thoroughly tight connection is guaranteed.

In the form shown in Fig. 7 of the drawing, the adjusting nut 41' is provided with a series of recesses 42' in one end thereof, instead of the notches or recesses in the peripheral surface as shown in Figs. 5 and 6 of the drawing, and the adjacent end of the section 39 carries a spring-actuated bolt or latch 43' mounted in a longitudinal seat or bored out portion of the section communicating with the opening 42, the latch or bolt being operated by the spring 44' to engage one of the respective notches in order to hold the nut against rotation, but adapted to be displaced by means of a finger piece 45' branching from the latch or bolt and operable exteriorly of the section at the top thereof instead of at the side as shown in the other form.

By proper adjustment or by adjusting the stroke of the piston so as to shorten the length thereof, whereby to prevent total closing or seating of the valve during the forward stroke or movement of the piston while the door is closing, a single primary cushion will be formed or produced, and

by further adjustment of the stroke of the piston, said cushion may be shortened or lengthened when solely in play. When however, the stroke of the piston is lengthened sufficiently to produce and cut into the positive cushion formed by the complete closing or seating of the valve and after the valve is closed to totally cut off the escape of the liquid or fluid through the by-pass or passage, a plurality of distinct cushions will be produced and the other or positive second cushion of the plurality of cushions operative after the first cushion, may be regulated or adjusted, that is, shortened or lengthened, when a plurality of cushions are in play, independently of or so as not to change or alter the length, speed or strength of the first cushion formed.

From the foregoing description taken in connection with the accompanying drawings, it will be seen that there is provided a very efficient and simple form of door closer and check and particularly an adjusting and regulating mechanism which is simple and positive in operation, and which will be applicable to general forms of devices other than as specifically described.

Having now described my invention, what I claim as new and desire to secure by Letters Patent is:

1. In a door check and closer, the combination with a closing means and a checking mechanism having a cushion, and a post having adjustable connection with a stationary part; of means operative through the medium of adjustment of the connection and post for regulating the last part of the cushion, said adjustment being made while retaining the parts in operative connection at all times.

2. In a door closer and check, the combination with a closing means and a checking mechanism having a plurality of cushions, and a post having adjustable connection with a stationary part; of locking means operative through the medium of adjustment of the connection and post for regulating the length and time of one of the cushions, said locking means being adapted to be manually disconnected and automatically connected, and said adjustment being made while retaining the parts in operative connection at all times.

3. In a door closer and check, a closing means and a checking mechanism having a plurality of liquid cushions and a post provided with an arm, an adjustable link connected to the arm; of means operative through the adjustable link and post for regulating one of the cushions, said adjustment being made while retaining the parts in operative connection at all times.

4. In a door closer and check, the combination with a closing means and a checking mechanism constituting a cushioning

means, and a post; of means operative through the medium of the post for regulating the cushioning means to produce one or more cushions, and to shorten or lengthen 5 said one cushion when solely in play, and to shorten or lengthen the other of the plurality of cushions operative after the first cushion when a plurality of cushions are in play, independent of the length, speed or 10 strength of the first cushion formed.

5. In a door closer and check, a closing means, a checking mechanism including a piston forming a cushioning means, a passageway through the piston, a valve seated 15 in the passage-way and automatically controlling said passageway directly, a post having connection with the valve, for constantly moving the same during the movement of the post, an adjustable connection 20 carried by the post and operative through the same for regulating the cushioning means while maintaining the operative connection for producing one or more cushions and to shorten or lengthen said one cushion 25 when solely in play and to shorten or lengthen the second cushion when a plurality of cushions are in play.

6. In a device of the character described, a two chambered casing, a spindle rotatably 30 journaled through the chambers of said casing, an arm connected to the spindle, a tension spring contained in one of said chambers and having operative connections with the arm, a piston movable in the other chamber 35 and having valved passageways therethrough, said spindle having a cranked portion, a connecting rod between said cranked portion and piston, and a pivot connecting 40 said rod to the piston and provided with a single passageway forming a valve in association with the passageway through the piston.

7. In a device of the character described, a two chambered casing, a spindle rotatably 45 journaled through the chambers of said casing, an arm connected to the spindle, a tension spring contained in one of said chambers and having operative connections with the arm, a piston movable in the other chamber 50 and having valved passageways therethrough, said spindle having a cranked portion, a connecting rod between said cranked portion and the piston and having an apertured pivot portion intercepting a 55 passageway, said piston in the last mentioned chamber constituting a cushioning means in which the forward movement of the piston by oscillation of the crank and rod serves to open said valve by oscillation 60 of the pivot and alinement of the passageways, said pivot serving to close said valve at a predetermined time to prevent the free escape of fluid through the passageway intercepted by the pivot portion.

65 8. In a device of the character described,

a two chambered casing, a spindle rotatably journaled through the chambers of said casing, an arm connected to the spindle, a tension spring contained in one of said chambers and having operative connections with 70 the arm, a piston movable in the other chamber and having valved passageways therethrough, said spindle having a cranked portion, a connecting rod between said cranked portion and the piston and having 75 a pivot connecting to the latter, said piston in the last mentioned chamber constituting a cushioning means in which the forward movement of the piston by oscillation of the crank and rod serve to open said valve 80 by oscillation of the pivot and alinement of the passageways, said pivot serving to close said valve at a predetermined time to produce a positive cushion in front of said piston serving to check the free movement 85 thereof under the action of the spring and consequently the free movement of the arm, and means to vary the time of closing the valve by the arm through the medium of the spindle. 90

9. In a door check and closer, a cylinder, a piston operable in said cylinder, a movable part having operative connection with the piston, said connection including a spindle having a crank and a link having a 95 wrist pin pivotally connected with the piston, said piston having a plurality of passageways therethrough, a check valve controlling one of said passageways and a valve produced by the pivotal connection of the 100 link with the piston coöperating with one of said passageways, said pivotal connection having a passageway therethrough.

10. In a door closer and check, in combination, a cylinder, a piston operable in said 105 cylinder, a movable part having operative connection with the piston, said connection including a spindle having a crank and a link having a wrist pin pivotally connected with the piston, said piston having a plurality of passageways therethrough, a check 110 valve controlling one of said passageways, said wrist pin having a passage therethrough coöperating with the other passageway through the piston, and serving to gradually open and close the same during 115 the operative movements of the piston.

11. In a door check and closer, the combination with a closing means and a checking mechanism comprising a piston, a link 120 and a spindle pivotally connected to the piston through the medium of the link, said piston having an open passageway and a valved passageway therethrough, said piston having means coöperative with the open 125 passageway through the medium of the pivotal link on its forward stroke in producing automatically a plurality of successively operable cushions, and means through the medium of the spindle of regulating and 130

controlling the length or time of the closing action of the first one of said plurality of cushions without bringing the other cushions into operative action.

- 5 12. A door check comprising a liquid chamber, a piston in said chamber provided with an aperture for establishing communication with the chamber at opposite sides of the piston, a valve pivoted to operate in the 10 piston and coöperating with the passageway to control the flow of fluid therethrough, a spring actuated spindle and operative connections between the spindle and the valve for pivoting the latter during the 15 reciprocation of the piston, said valve having a passage therethrough adapted to be moved into and out of alinement with the passageway through the piston.

13. A door check comprising a liquid 20 chamber, a shaft, a rod, and a piston in said chamber, a passageway communicating with the chamber at opposite sides of the piston, and means including a pivoted rod movable with the piston for automatically 25 graduating the flow of liquid through the passageway, and thereby producing a plurality of cushions, and means of controlling one of said cushions through the medium of changing the position of the shaft independently 30 of time, speed and length of the other cushion and while the parts are in operative relation.

14. In a door closer and check, the combination with a closing and checking mechanism including a liquid chamber, a piston therein, a post having connection with the piston, means for operating the piston, a plurality of passageways through the piston, a check valve controlling certain of said 35 passageways, a separate valve directly co-operating with and automatically controlling the other passageway, a lever arm connected to the post, an adjustable link having pivotal connection with the extremity of 40 said arm, said link including a pair of sections telescoping with one another, means for adjusting said sections whereby to vary the length of the link while retaining the parts in operative connection at all times 45 and regulate the length or stroke of the piston through the post and thereby regulate the cushions produced thereby, and means for locking said adjusting means.

15. A door check comprising a liquid 55 chamber, a crank shaft, a pivotal rod, and a piston in said chamber, there being a passageway through the piston and communicating with the chamber at opposite sides of the piston, and means of controlling the flow 60 of the liquid through said passageway by the pivotal rod movable with the piston to automatically control and graduate the flow of the liquid through said passageway during the forward movement of the piston and 65 thereby produce two distinct separate

cushions, a primary graduating cushion and a positive cushion, and means of regulating and controlling the positive cushion independently of the operation of the primary cushion.

- 70 16. A door check comprising a liquid chamber, a crank shaft, a pivoted rod, and a piston in said chamber, and having a passageway therethrough, means for controlling the flow of the liquid through the passageway by the pivoted rod movable with the piston to automatically control and graduate the flow of the liquid through said passageway during the forward movement 75 of the piston to produce a primary cushion 80 and thereafter, a positive cushion gradually brought into operation, and means of regulating and controlling the positive cushion while maintaining a constant primary cushion through manually turning and locking the position of the crank shaft, whereby the travel of the piston at or near the finish of the stroke will be effected, shortened, or lengthened.

- 85 17. In a door closer and check, the combination with a closing means and a checking mechanism comprising a spindle, a piston, a link, said link having pivotal connection to the spindle and piston, said piston being provided with an open passageway and a plurality of valved passageways therethrough, said open passageway having cooperative means through the medium of the pivotal link in its operative action in producing automatically a plurality of cushions, 90 and means through the medium of the spindle of regulating and controlling the length or time of the second of the plurality of cushions independent of manual adjustment of said coöperative means and while 95 maintaining the operative connections of the parts.

- 100 18. In a device of the class described, a cylinder, a piston operable in said cylinder, a movable part having operative connection with the piston, said connection including a spindle having a crank and a link between the crank and the piston, said piston having an open passageway therethrough and valved communication with the cylinder at 105 opposite sides of the piston, said open passageway having cooperative means through the medium of the pivotal link in producing a plurality of cushions, means operative through the spindle to shorten or lengthen 110 the stroke of the piston, said adjustment being made while retaining the parts in operative connection at all times, and means to positively lock the parts in adjusted positions.

- 115 19. In a device of the class described, a cylinder, a spindle, a piston movable in said cylinder, a pivotal movable part having operative connection with the spindle and the piston, said piston being provided 120 125

with an open passageway and a plurality of valved passageways therethrough, said open passageway having means coöperative through the pivotal movable part whereby 5 in its operation a plurality of cushions are automatically produced and means operative through the medium of the spindle for regulating and controlling the means co-operative with the open passageway and 10 said plurality of cushions.

20. A door check comprising a liquid chamber, a piston therein, means for operating the piston, a plurality of valved passageways and an open passageway communicating with the chamber at opposite sides of the piston, an oscillating device movable with the piston for automatically controlling the flow of the liquid through the open or valveless passageway and to 15 completely close said passageway and thereby automatically produce in its operating a plurality of cushions.

21. A door check comprising a liquid chamber, a piston therein, means for operating the piston, a single passageway, and a valved passageway communicating with the chamber at opposite sides of the piston, and an oscillating device movable with the piston for automatically controlling the flow 25 of the liquid through said valveless passageway and to totally close said passageway at a predetermined time and thereby automatically produce in operation a plurality of cushions, one of which is positive.

30. 22. A door check comprising a liquid chamber, a horizontally operating piston therein, means for operating the piston, a valved passageway and an open passageway communicating with the chamber at opposite sides of the piston, an oscillatory device 35 movable with the piston for automatically controlling the flow of liquid through said open passageway and thereby producing in operation a plurality of cushions and means for adjusting the movement of the oscillatory device through regulation of the stroke of the piston.

23. A device of the character described, comprising a fluid chamber, a piston in said 40 chamber, means for operating the piston, an open passageway and a plurality of operating valved passageways communicating with the chamber at opposite sides of the piston, an oscillating device controlling the flow of 45 the liquid through said open passageway and means movable during the reciprocation of the piston for controlling said device to automatically regulate the flow of the fluid through said open passageway whereby the 50 passageway is opened during the initial movement of the piston but completely closed during the final closing movement of the piston.

24. A door closer and check, a liquid 55 chamber, a spindle, a link and a piston piv-

otally connected together in said chamber, there being a passageway communicating with the chamber at opposite sides of the piston, an arm on the spindle, means including the pivotal link, movable with the piston for automatically graduating the flow of the liquid through the passageway and to close the same thereby producing a plurality of cushions and adjustable locking means for controlling and regulating the length or time of one of said cushions through the medium of changing the position of the arc turned by the spindle by the arm while the parts are in operative relation.

25. In a door check and closer, the combination with a closing means and a checking mechanism having a cushion and a post having adjustable connection with a stationary part; of means operative through the medium of physical adjustment of the connection for thereafter automatically regulating the last part of the cushion without disturbing the operative positions of the parts.

26. In a door check and closer, the combination with a closing means and a checking mechanism having a cushion, and a post having adjustable connection with a stationary part; of means operative through the medium of physical adjustment of the connection and post, thereby providing a plurality of cushions and regulating one of the cushions without perceptibly affecting the other cushion.

27. In a door closer and check, the combination with a closing means and a checking mechanism having a plurality of cushions and a post having adjustable connection with a stationary part; of means operative through the medium of adjustment of the connection and post for regulating one of the cushions without disturbing the operative condition of the connection and parts associated therewith and locking means for securing the parts against accidental movement.

28. In a door closer and check, the combination with a closing and checking mechanism including a liquid chamber, a piston therein, a post having connection with the piston, spring means for operating the piston, a plurality of passageways through the piston, a check-valve controlling one of said passageways, a separate valve associated with the connection between the post and piston and controlling the other passageway, a lever arm connected to the post, an adjustable link having pivotal connection with the extremity of said arm, means for adjusting the length of said link without disturbing the connection thereof with the arm and means to lock said last named means against turning when adjusted.

29. In a door check and closer, the combi-

nation with a closing means and a checking mechanism having a piston; of means including an automatically actuated valve carried by the piston for automatically closing a passageway through the same gradually and at a predetermined time entirely closing said passageway to produce a plurality of distinct cushions during the movement of the piston while the door is closing, one of said cushions at least, being positive or capable of control, and said means being operative independently of manual adjustment of mechanism within the casing and adapted to be adjusted independently of physical working valves.

30. In a door check and closer, a casing divided into two chambers, a spring in one of said chambers, a piston in the other of said chambers and having operative connection with the spring to cause the actuation of the piston, a single valve means associated in the connection to produce a plurality of cushions during the forward movement of the piston, one of which is of sufficient density or resistance as to be capable of control as to its length, time and speed, said cushions being produced in the mechanism automatically during the movements of the parts entirely during the operation of the check in closing.

31. In a door check and closer, the combination with a closing means and a checking mechanism having a post and a piston operatively connected thereto; of means for establishing valved-communication between the spaces or chambers at opposite sides of the piston, a single valve for causing the automatic production of a plurality of cushions during the operation of the check, one of which is positive and of sufficient strength to be capable of being regulated, and means for regulating the stroke of the piston and operation of the valve.

32. In a door check and closer, a casing divided into two chambers, a spring chamber and a piston chamber, a spindle journaled to extend through said chambers and having adjustable connection with a part to be operated, there being a passageway or bypass communicating with the opposite ends of the piston chamber, a piston in the chamber and operatively connected with the spindle, and a valve coöperating with the passageway to produce a plurality of successive graduating cushions automatically during the forward movement of the piston, said passageway being automatically and entirely cut off when the piston is near the end of its stroke to produce a positive cushion offering strong increased resistance to the movement of the piston with subsequent escape of fluid between the piston and casing during the operation of the last cushion.

33. In a door check and closer, the combination with a cylinder adapted to contain a

cushioning fluid, a piston working in said cylinder and provided with a post in operative connection therewith, there being a passageway communicating with the cylinder at opposite sides of the piston; of means for operating the piston by turning the post, said piston producing a relatively constant primary cushion during the first part of its movement, and means whereby when the piston reaches a point near the limit of its movement said passageway will be completely closed to form a minutely adjustable positive cushion operative after said primary cushion.

34. In a door check and closer, a casing divided into two chambers, a spring chamber and a piston chamber, a spindle journaled to extend through said chambers and having adjustable connection with a part to be operated, said adjustment being capable independently of disconnection of the parts, said spindle having a crank, a piston in the chamber having valve connection with the crank to produce a plurality of successive graduating cushions automatically during the forward stroke of the piston, independent valve communication between the spaces at opposite sides of the piston adapted to be established during the opposite stroke thereof, said valve serving to totally cut off the passage through the piston near the end of its stroke with subsequent escape of fluid around or past the piston during the operation of the last cushion.

35. In a device of the character described, a two-chambered casing, a spindle rotatably journaled through the chambers of said casing, an arm connected to the spindle, a tension spring contained in one of said chambers and having operative connection with the arm, a piston movable in the other chamber and having valved passageways therethrough, said spindle having a crank portion, a connecting rod between said crank portion and the piston and having a pivot connecting to the latter, said piston in the last mentioned chamber constituting a cushioning means in which the forward movement of the piston by oscillation of the crank and rod serves to open said valve by oscillation of the pivot and alinement of the passageways, said pivot serving to close said valve at a pre-determined time to produce with the primary cushion, a plurality of cushions, one of which is positive.

36. In a device of the character described, a two-chambered casing, a spindle rotatably journaled through the chambers of said casing, an arm connected to the spindle, a tension spring contained in one of said chambers and having operative connection with the arm, a piston movable in the other chamber and having valved passageways therethrough, said spindle having a crank portion, a connecting rod between said crank

portion in the piston and having a pivot connecting to the latter, said piston in the last mentioned chamber constituting a cushioning means in which the forward movement of the piston by oscillation of the crank and rod serves to open said valve by oscillation of the pivot and alinement of the passageways, said pivot serving to close said valve at a pre-determined time to produce 10 with the primary cushion, a plurality of cushions, one of which is positive and means to vary the time of closing the valve by the arm through the medium of the spindle.

37. In a door closer and check, the combination with a closing means and a checking mechanism constituting a cushioning means, and a post; of means operative through the medium of the post while retaining said parts in operative connection at all times; 15 for regulating the cushioning means to produce one or more cushions and to shorten or lengthen said one cushion when solely in play and to shorten or lengthen one or the other of the plurality of cushions operative 20 after the first cushion when a plurality of cushions are in play, one of said cushions being positive.

38. In a door check and closer, the combination with a hinged door; of a cushioning 30 device comprising a cylinder, a piston operating therein, a post operatively connected therewith, means for establishing valved communication with the interior of the cylinder at opposite sides of the piston to permit free rearward movement thereof and 35 check the forward movement thereof, a passageway communicating with the interior of the cylinder at opposite sides of the piston, and means coöperative with the piston during 40 the forward movement thereof to produce a plurality of distinct cushions successively and to completely close said passageway so that the last cushion formed when the piston is near the end of its stroke is 45 positive.

39. In a door closer and check, the combination with a checking mechanism including a liquid chamber, a piston therein, a post having connection with the piston, spring 50 means for operating the piston, a plurality of valved passageways and an open passageway through the piston, a checking valve controlling the said open passageway associated with the connection between the post, 55 and piston and controlling the said open passageway, an arm connected to the post, an adjustable link connected to the extremity of the arm, means for regulating the arc turned by the arm through the medium of 60 the adjustable link, said adjustment being made while retaining the parts in operative connection at all times, and means to lock said link from moving whereby the arc turned by the arm in its operation will be 65 under positive control.

40. In a door closer and check, the combination with a checking mechanism, including a liquid chamber, a piston therein, a post having connection with the piston, spring means for operating the piston, a 70 valved passageway and an open passageway through the piston, a checking valve controlling the said open passageway associated with the connection between the post and piston and controlling the said open passageway, an arm connected to the post, an adjustable link connected to the extremity of the arm, means for adjusting and rigidly locking said link and unlocking while retaining the parts in operative connection at 75 all times, whereby the arc turned by the arm in its operation will be under positive control.

41. In a door closer and check, the combination with a checking mechanism including a liquid chamber, a piston therein, a post having connection with the piston, spring means for operating the piston, means to establish valved communication between the spaces at opposite sides of the piston, a passageway through the piston, means coöperating with the passageway to produce a plurality of cushions during the forward stroke thereof, articulated means associated with the post and means to adjust said articulated 90 means for varying the arc swung by the post during the operation of the check and regulating the cushions produced thereby.

42. In a door closer and check, the combination with a checking mechanism including a liquid chamber, a piston therein, a post having connection with the piston, means for operating the piston, means to establish valved communication between the spaces at opposite sides of the piston, a passageway through the piston, means coöperating with the passageway to produce a plurality of cushions during the forward stroke thereof, and articulated means capable of longitudinal adjustment and anchorage in 100 any adjusted position for regulating the stroke of the piston and the length, time and action of the cushions produced during the forward stroke of the piston.

43. In a door closer and check, the combination with a checking mechanism including a liquid chamber, a piston therein, a post, and connection affording means of connection of the post with the piston, spring means for operating the piston, a plurality of valved passageways and an open passageway through the piston, a check valve controlling the said open passageway associated with the connection between the post and piston and controlling the said open passageway, an arm connected to the post, an adjustable link connected to the extremity of the arm, and means to vary the arc swung by the arm, the stroke of the piston and cushions produced thereby.

44. In a door check and closer, the combination with a spring door closing means, and a checking mechanism, said mechanism having a plurality of cushions operative during the closing operation, a post having adjustable connection with a door or lintel; means operative through the medium of adjustment of the connection and post for regulating one of the cushions without disturbing the operative condition of the connection and parts associated therewith, and automatic locking means associated with the adjustable connection to secure the same in adjusted position when regulating one of the cushions.
45. In a door check and closer, a casing divided into two chambers, a spring chamber and a piston chamber, a spindle journaled to extend through said chambers and having adjustable connection with a part to be operated, a piston in the piston chamber

having valved connection with the post, to produce a plurality of successive graduating cushions automatically during the forward stroke of the piston, independent valve 25 communication between the spaces at opposite sides of the piston adapted to be established during the opposite stroke thereof, said first named valve serving to totally cut off the passage through the piston near the 30 end of its stroke with subsequent escape of the fluid around or past the piston during the operation of the last cushion.

In witness whereof I have hereunto set my hand at the borough of Manhattan, city 35 and State of New York, this fourth day of May, 1915.

WILLIAM J. BRYON.

In presence of—

JOHN J. RANAGAN,
FRANK EUFEMIA.
